UNITED STATES PATENT OFFICE.

SIMEON TURNER, OF WARREN, INDIANA.

AUTOMATIC RAILWAY-GATE.

1,243,643.

Specification of Letters Patent. Patented Oct. 16, 1917.

Application filed January 31, 1917. Serial No. 145,745.

To all whom it may concern:

Be it known that I, SIMEON TURNER, a citizen of the United States, residing at Warren, in the county of Huntington and State of Indiana, have invented new and useful Improvements in Automatic Railway-Gates, of which the following is a specification.

This invention comprehends improvements in automatic railway crossing gates and relates particularly to that type of crossing gate which is closed by the approach of a train toward the crossing and opened by the train as it passes beyond the crossing.

One of the objects of the invention is to provide a simple practical and substantial automatically operated gate of this type wherein a plurality of track trips are provided for engagement by the wheels of a train to operate a shift rod which controls the movements of weights connected to the gates for opening and closing the latter.

A further object of the invention is to provide automatic gate operating mechanism which will operate to release weights to lower the gates when a train is approaching the crossing from either direction and which will automatically raise the weights as the train recedes from the crossing to permit the gates to open.

The invention also aims to generally improve automatic crossing gate mechanism to render it more substantial, useful and practically desirable.

With these and other objects in view as will become more apparent as the description proceeds, the invention consists in certain novel features of construction, combination and arrangement of parts as will be hereinafter fully illustrated, described and claimed.

In the drawings,

Figure 1 is a top plan view of the automatic railway gate.

Fig. 2 is a side elevation showing the gate closed.

Fig. 3 is a side elevation showing the gate open.

Fig. 4 is a detail perspective view of one set of track mechanism showing a wheel in the act of engaging a trip to open the gate.

Fig. 5 is a view similar to Fig. 4 showing the parts in position to close the gate.

Fig. 6 is a detail perspective view of the

weight lifting mechanism on one of the gate posts.

Fig. 7 is a fragmentary top plan view showing one set of the track mechanism.

Referring in detail to the drawings by numerals, 1 designates the cross ties, 2 the rails and 3 the gate posts at the crossing. Each of these posts is formed by a pair of uprights 4 firmly fixed in the ground and between each pair of uprights is pivotally mounted a mast gate 5 of the usual construction having the weights 6 on its butt end which are of sufficient size to swing the gate into a vertical position when released.

The mechanism on one side of the track will first be described in detail. Here as shown, a weight 7 is pivoted as at 8 between the uprights of each of the posts 3 and these weights which extend toward each other are connected by chains 9 or other suitable fastening members to the gates 5. The chains 9 are of such a length as to hold the weights 7 in a substantially horizontal position when the gates are closed as shown.

For the purpose of raising the weights to permit of the gates opening under the influence of the gate weights 6, I provide a forked lifting lever 10 for each weight. Each lever is pivotally mounted as at 11 between extensions 12 on each of the posts. These extensions serve to space the weight levers a slight distance from the posts to allow an operating means to work through the slots 13 in their lower ends.

Extending along the track above the cross ties 1 is a main shifting rod 14 mounted on roller bearings 15 and slideable between the roller bearings 16. This rod is pivotally connected to a lever 17 which is pivotally secured intermediate its ends as at 18 and 95 which projects through the forked end of the corresponding weight lifting lever 10. To operate the weight lever on the opposite side of the crossing, I provide an arm 19 rigidly secured to the shift rod 14. This arm moves over the stationary slide 20 and projects through the forked end of the corresponding weight lifting lever 10 to actuate the same.

The shift rod 14 is formed in two sections 21 and 22 which sections are connected at their opposed ends by the pivoted reversing lever 23. To operate the shift rod 14, I provide on each side of the crossing a track trip 24 pivotally secured to the rail as indi- 110

cated at 25. Each of the trips 24 is formed with a wheel engaging face 26 and an arm engaging face 27. The upper end of the trip is of a reduced size and projects slightly above the wall of the rail to be engaged by the walls of an approaching train and the lower end of the trip is of enlarged cam shape. An arm 28 is pivotally secured at one end to a base plate 29 and at its other end to the shift rod 14. This arm 28 is engaged by the face 27 of the track trip and to reduce friction at the point of contact between these two members, I provide the arm with a plurality of anti-friction rollers 30. When a train approaches the crossing from either direction it will engage one of the track trips 24 causing it to swing about its pivot and shift the corresponding arm 28 toward the train. This movement of the arm 28 causes a movement of the shift rod 14 to rotate the weight lever 10 and permit the weights to lower thereby closing the gates.

To open the gates after a train has passed a crossing, I provide on each side of the crossing a track trip 31 which is pivoted to the rail as at 32 and which is of the same design as the track trips 24 having a wheel engaging face 33 and the arm engaging face 34. An arm 35 is pivoted at one end to each of the plates 29 and at its other end to the shift rod 14. Each of these arms engages the corresponding track trip 31 and are provided with anti-friction rollers 36. As a train leaves a crossing it engages one of the trips 31 swinging it so as to shift the corresponding arm 35 in the direction of the approaching train which motion is transmitted to the shift rod 14 to operate the weight lifting levers 10 to raise the weights 7 and allow the gates to swing open. It will be noted that the track trips are arranged in bearings and that the trips in each bearing are mounted to face in opposite directions. When one of the trips of a bearing is operated by a train it causes the other trip in the bearing to be swung into an inoperative position so as to let the wheels pass idly over the same. To operate the gates on the opposite side of the track from that just described, similar operating means are provided with the exception of the track trips and the trip engaging arms which may be omitted. A shift rod 37 similar to the shift rod 14 is used and is operated from the shift rod 14 by the cross tie rods 38. To eliminate friction as far as possible, all of the pivots are formed with roller or ball bearings and to protect the working parts from dust, grit and other accumulations, a suitable casing or housing, not shown, may be employed.

From the foregoing description taken in connection with the accompanying drawings it will be seen that I have provided a very

substantial and practical automatic gate operating mechanism in which track trips are provided for actuating a shift rod which will cause weights to be raised and lowered to open and close the crossing gates.

70

While I have shown and described the preferred embodiments of my invention it will be clearly understood that I do not wish to be limited to this construction, but may make such changes as will fall within the scope 75 and spirit of the invention as claimed.

What I claim is:

1. The combination with the post and gate bar of a gravity opened gate, of a weight having one end pivoted to the gate-post and the other end linked to the gate-bar; a device normally disposed in the path of movement of the weight for holding said other end of the weight elevated to permit the gate-bar to maintain the open position, said device having a mounting whereby it is adapted to be moved out of the path of the weight, and means for moving said device out of the path of the weight to permit the weight to move the gate-bar to the closed position. 90

2. The combination with the post and gate-bar of a gravity opened railroad crossing gate, of a weight having one end pivoted to the gate-post and the other end linked to the gate-bar, a lever pivoted to the gate-post with one end engaging against the bottom of the weight, and car-operated means for moving said lever to permit said weight to close the gate, said means and said lever normally holding said weight in a position 100 to permit the gate to remain open.

3. In a railroad crossing gate mechanism, a pair of gate-bars, posts upon which said bars are pivotally secured, weights carried by the gates for opening the same, gate 105 closing weights having one end of each pivoted to a respective post, link means connecting the other end of each weight to the respective bar, a lever pivoted to each post with one end engaging against the respective closing weight, a shift rod connected to said levers, a track trip on each side of the crossing, means operated by each of said track trips for moving the shift rod in one direction, a second set of trip rods on opposite 110 sides of the trackway, and means operated by said second set of trip rods for moving the shift rod in the opposite direction.

4. In a railway crossing mechanism, a pair of crossing gates, posts pivotally supporting 120 said gates, weights carried by the gates to swing the same into open position, weights pivoted on the posts and connecting the gates to swing the same into closed position, weight levers mounted on the posts to operate said second mentioned weights, a shift rod, means operated by the shift rod for actuating said weight levers, a track trip on each side of the crossing, means operated by each of said track trips for moving the 130

shifted rod in one direction, a second set of track trips on opposite sides of the crossing, and means operated by the second set of track trips for moving the shifted rod in 5 the opposite direction.

5. In a railway crossing mechanism, a pair of crossing gates, posts upon which said gates are pivotally secured, weights carried by the gates for opening the same, 10 gate closing weights secured to the posts, a shift rod, means actuated by said shift

rod for operating said second mentioned weights, a track trip on each side of said crossing, means operated by each of said track trips for moving the shift rod in one 15 direction, a second set of track trips on opposite sides of the crossing and means operated by said second set of track trips for moving the shift rod in the opposite direction. 20

In testimony whereof I affix my signature.
SIMEON TURNER.
